J. D. McEWEN

JACK FOR DERRICK LEGS

Filed Dec. 19, 1924

Fig. 1.

UNITED STATES PATENT OFFICE.

JOHN D. McEWEN, OF PITTSBURGH, PENNSYLVANIA, ASSIGNOR TO LEE C. MOORE & COMPANY, INC., OF PITTSBURGH, PENNSYLVANIA, A CORPORATION OF PENNSYLVANIA.

JACK FOR DERRICK LEGS.

Application filed December 19, 1924. Serial No. 756,955.

This invention relates to derricks for oil wells and the like. More particularly the invention relates to reinforcing or supplementary legs adapted to be used with a permanent steel derrick tower for the purpose of strengthening it during the drilling of a well, but intended to be removed after the well is finished. More particularly still the invention relates to means for adjusting the length of such supplementary or reinforcing derrick legs.

The objects of the invention are to provide an extensible member or jack, adapted to be positioned in the reinforcing legs of a derrick, whereby the length of the supplementary leg may be adjusted to insure the carrying of its proper part of the derrick load. The specific objects and advantages of the invention will appear more fully from a consideration of the following specification and the drawings.

Referring to the drawings, Fig. 1 is a side view of the two legs forming the corner of a well drilling derrick, as when the permanent tower is reinforced with supplementary legs, the adjusting jack of this invention being applied to the reinforcing leg; and Fig. 2 is an enlarged vertical section through the jack and the leg sections to which it is applied.

In building steel derricks for oil wells it has been found that the derrick necessary to support the drilling operation is much stronger than is required after the well is completed, for maintenance purposes, such as pumping, etc. In recent years the practice has arisen of erecting a light steel derrick tower, of sufficient strength for maintenance purposes, but not strong enough for drilling operations, and then temporarily reinforcing the legs of this light derrick by additional legs attached to the permanent ones, these reinforcing legs being used only until drilling is completed. They may then be removed. Should conditions at any later time require a stronger derrick, the reinforcing legs may be replaced as in the first instance.

There has existed in such construction a difficulty in adjusting the lengths of supplementary legs so as to bring them under the proper compression to carry their part of the load. This has ordinarily been done by driving wedges under the lower ends of the

supplementary legs and then placing supporting shims thereunder. But there is difficulty in using such shims of less than one-eighth inch thickness and consequently there has been considerable trouble in securing the proper adjustments of length of the permanent and reinforcing legs. It is to meet this problem that the present invention is designed.

Referring to the drawings, Fig. 1 shows a base casting 1 for use at each corner of a tubular steel derrick for oil well drilling. This casting is of course seated upon a suitable base or foundation, and it supports in a socket the permanent tubular leg sections 2, placed end upon end and clamped together in well known manner. At the top, castings 3 are positioned on the tubular leg members for attaching to the upper terminal structure of the derrick. Clamps 4 are attached to the leg sections 2 and to these clamps by means of tongues 5—5, and 6, are attached braces and girts extending to adjacent legs, in well understood manner. The clamps themselves are held on the leg sections by means of compression bolts 7.

The supplementary or reinforcing legs to be used for strengthening the derrick during drilling operations are formed of leg sections 10, preferably tubular in form. The lowermost of these seats over a retaining lug 11 positioned on the upper face of the casting 1, and the reinforcing leg is attached to the permanent leg by means of U-shaped loops 12, extending around the two legs and clamping them together by means of terminal cross members 13 and nuts 14. Wedge shaped spacers 15 are positioned between the tubes, all as clearly shown in Fig. 1. This particular construction is no part of the present invention.

In order to secure proper adjustment of the reinforcing leg made up of the sections 10, I position between any two convenient adjacent sections a jack construction, illustrated in detail in Fig. 2.

This comprises a nut 20 having a knurled head, and a concentric extension 21 adapted to fit inside the lower end of one of the tubular sections 10^a, the tube end seating upon a shoulder formed between the head 20 and extension 21, as clearly shown in Fig. 2. The extension 21 has a threaded hole tapped therein, for receiving a set screw 22, the

head of which is adapted to be positioned in an opening 23 in the lower end of the tube 10^a. When the set screw is in position as shown in Fig. 2 it effectively locks the nut 5 in the lower end of that section, keeping it from falling out, and also preventing its rotation.

A screw 25 is threaded through a central bore in the nut above described. The lower 10 end of this screw is tapered, and adapted to have secured thereon a knurled head 30, retained rigidly on the screw by means of a locking pin 31. Holes 32 and 33 extend through the head 30 and the screw 25, as 15 illustrated. The outer periphery of the member 30 is knurled. Its lower face has an extension 34, of a diameter sufficient to permit it to seat in the upper end of the tubular leg section 10.

20 A clamp 40 consisting of a single plate in circular form, with the edges extending tangentially outward to form flanges 41 having registering perforations 42 therein is provided.

25 The operation and use of this device is as follows: It will be understood that the derrick is first erected with the legs 2, suitably connected by cross braces, etc. Then the reinforcing leg is built up by positioning the 30 leg sections 10 at any convenient point, usually near the top of the derrick; clamp 4 is slipped over the uppermost of these leg sections; the jack member is positioned at the top of the uppermost section; the next 35 section 10^a is then positioned on the jack, as shown in Fig. 2 and succeeding leg sections are positioned and clamped together in normal manner. The uppermost leg section 10^b bears against the lower face of the terminal casting 3. In order to extend the 40 reinforcing leg to cause it to carry its part of the load, the set screw 22 is positioned, thus locking the nut 20 against rotation in the leg sections 10^a. A pin is then inserted through 45 one of the holes 32 or 33, and the head 30 is rotated, driving the screw 25 in the nut 20, in a direction to raise the nut. The jack is turned up until the proper pressure is obtained on the reinforcing leg. Then the 50 driving pin is removed, the clamp 40 is raised until it covers the two knurled por-

tions 20 and 30, and it is clamped in position to grip both of those knurled surfaces, thus locking them in fixed relative position.

When the well has been completed and it 55 is desired to remove the reinforcing legs, the clamp 40 is loosened and lowered, the head 30 is turned in reverse direction to release the screw pressure, and this permits ready removal of the reinforcing legs.

While I have illustrated and described a 60 tubular derrick, modifications can be made in the jack adapting it for use with any type of legs built up of sections.

I claim:

1. The combination with a sectional leg 65 for derricks of a jack screw having a fixed head adapted to engage one end of the leg section and a rotatable nut adapted to engage the end of an adjacent leg section, and a clamp adapted to engage the peripheries of the head and nut to hold them in adjusted position.

2. The structure described in claim 1 70 further characterized by the fact that the said head and nut have knurled peripheries for engagement by the said clamp.

3. The combination with a leg for derricks of a jack screw adapted to vary the 75 length of the said leg, said screw having a relatively rotatable nut adapted to engage the end of one leg section, means to attach the nut to the leg section, a fixed head on one end of the screw, said head being adapted to engage the end of an adjacent leg section and be rotatable in respect thereto, and a clamp adapted to engage the said head and nut to prevent relative rotation thereof.

4. The combination with a sectional leg 80 for derricks of a jack screw having a fixed head adapted to engage one end of a leg section, and a rotatable nut adapted to engage the end of an adjacent leg section.

5. The combination with a tubular sectional leg for derricks of a jack screw having a fixed head adapted to fit into and be attached to one end of a leg section, and a rotatable nut adapted to engage the end of an adjacent leg section.

In testimony whereof, I sign my name.

JOHN D. McEWEN.
